UNITED STATES PATENT OFFICE.

CHARLES F. DAUSMANN, OF BROOKLYN, NEW YORK, ASSIGNOR TO THE PRISMATONE CO., INC., OF NEW YORK, N. Y., A CORPORATION OF NEW YORK.

PRINTING PRESS.

Application filed November 3, 1919. Serial No. 335,420.

To all whom it may concern:

Be it known that I, CHARLES F. DAUSMANN, a citizen of the United States, and a resident of the borough of Brooklyn, ⁵ county of Queens, city and State of New York, have invented certain new and useful Improvements in Printing Presses, of which the following is a specification.

The present invention relates to improvements in printing presses, and particularly to presses of the rotary gravure type in which an etched intaglio printing cylinder cooperates with a yieldable impression roller, and between which the sheet or ¹⁰ web of paper is fed. The improvements contemplated herein are especially adapted to use in a press including a plurality of superimposed printing units, through which the paper is fed and printed successively in ¹⁵ a plurality of colors. It is obvious that in a press of this type, great accuracy is essential and absolute registration of the cylinders necessary to insure the proper printing of the different colors upon the paper ²⁰ in exact superimposed relation.

It is a primary object of my invention therefore, to provide means capable of accurate and positive adjustment of the printing cylinder longitudinally and circumferentially to effect the registration thereof, such means being convenient and facile of ³⁰ operation and permitting of adjustment to the very finest degree.

I further propose to provide an improved doctor knife for removing or wiping excess ink from the printing cylinder, and transmission means disposed between the printing cylinder and the doctor for effecting its movement over the cylinder, to the end that the movement of the doctor will be properly timed to the movement of the cylinder and a thorough and even removal of the ink results. A further object of my invention is to enable the removal of the printing cylinder with facility, and to this end I propose to provide a carriage at each end thereof cooperatively connected together, and which may be moved toward or away from the impression rollers, the cylinder in the outer ⁴⁰ position of the carriages being free to be removed. I further propose to enable the adjustment of the pressure relation between the printing cylinder and the impression roller ⁴⁵ ⁵⁰

and also between the doctor and the printing cylinder. ⁵⁵

A still further object is to provide an improved ink font, the inking roller of which may be engaged with and disengaged from the printing cylinder with facility, and may further be accurately adjusted as to its pressure relation therewith. In general my improvements enable the accurate and positive adjustment of the printing cylinder and parts cooperating therewith with the greatest precision, and at the same time in a manner as to maintain the adjustment against the effects of vibration and other forces set up by the operation of the press. ⁶⁰ ⁶⁵

With these and other objects in view, an embodiment of my invention is shown in the accompanying drawings, and this embodiment will be hereinafter more fully described with reference thereto and the invention will be finally pointed out in the claims. ⁷⁰

In the accompanying drawings, ⁷⁵

Fig. 1 is a front side elevation of a press according to the present embodiment of my invention, and showing one printing unit;

Fig. 2 is a rear side elevation thereof;

Fig. 3 is an end view of the press with ⁸⁰ parts broken away;

Fig. 4 is a view of the printing cylinder and associated parts partly broken away and with parts in section;

Fig. 5 is a detail plan view of the driving gear at one end of the printing cylinder ⁸⁵ shaft;

Fig. 6 is an end view of the other end of the printing cylinder and showing means for adjusting the same longitudinally; ⁹⁰

Fig. 7 is a detail sectional view of a ratchet and pawl mechanism employed, and

Fig. 8 is a side elevational view of a printing press showing one embodiment of my invention incorporated therein, certain well ⁹⁵ known parts of the press being omitted for the sake of clearness.

Similar reference characters indicate corresponding parts throughout the several figures of the drawings. ¹⁰⁰

Referring to the drawings, the press according to the present embodiment of my invention comprises a pair of side frames or standards 10 and 11 of suitable height depending upon the number of superimposed printing units, each unit being supported ¹⁰⁵.

upon a corresponding structural formation of the frames. In the drawings I have only shown the portions of the frame supporting one unit, it being understood that the superimposed units are of similar construction.

The frames are respectively provided with horizontal step portions 12 terminating at their inner ends in enlarged rectangular pockets or recesses 13 provided in their lower and upright sides with adjustable screws 14 and 15 the screws 14 support the bearing blocks 16 of the printing cylinder 17, the shaft 18 of which rests in the pockets 19 formed in the said blocks, the bearing blocks together with the cylinder adapted to be moved into and out of printing position by means presently to be referred to. The screws 15 serve as abutments to limit the inward movements of the bearings 16.

20 The step portions of the side frames are each provided longitudinally with a channel 20 and at their upper sides there is slidably mounted a carriage 21 slightly wider than the step portion and provided with overhanging guide flanges 22 and 23, an upstanding head 24 being provided at the inner end of the carriage and having a vertical slot 25 formed therein in which is removably engaged a coupling head or stud 26 upon the bearing block 16, the connection causing the bearing block to move with the carriage while at the same time permitting vertical adjustment thereof.

At the under side of the carriage there is provided a projecting block or nut portion 27 disposed in the channel 20 and provided with a threaded passage 28 engaged by an elongated screw 29 journaled at the forward end of the channel in a bearing plate 30 fixed by bolts 30^a across the said forward end of the channel, the screw being held against longitudinal movement by shoulders 31 and 32 provided thereon. The shank of the screw extends forwardly and has fixed thereon a ratchet gear 33 engaged by a spring pressed ratchet tooth or pawl 34 mounted in a lever arm 35 rotatably supported upon the end of the shank. The lever at one side of the press is connected to the lever at the other side by means of a bar 36 pivotally secured at its ends upon studs 37 formed upon the levers, and adapted to impart equal movement from one lever to the other. By giving a to and fro swinging movement to one of the levers 35, both screws 29 are simultaneously and equally rotated, and longitudinal movement is thereby given to the carriages. The pawl 34 is such that it may be withdrawn from engagement with the gear 33 and reversed in position to cause rotation of the screw in either direction. As shown in Fig. 7, its shaft 38 is circular in cross section and reciprocates in a circular passage 39, being provided with a reduced shank having a knob 40 at its ex-

posed end, a spring 41 being disposed about the shank within the passage and abutting a shoulder 42 at the lower end of the passage. Diametrically opposite slots 43 and 44 are provided longitudinally in the wall of the passage in communication at their lower ends with an annular slot 45. A pin 46 in the shaft engages either one of the slots 43 and 44 and may be changed to the other to reverse the position of the nose of the pawl 75 by drawing the shaft down so that the pin may be turned through the annular slot 45. It will be manifest from the foregoing that if both of the pawls are similarly disposed with relation to the ratchets 34, the screws 29 are simultaneously and equally rotated. If, however, one of the pawls is withdrawn from engagement with the corresponding ratchet or the pawls are disposed in reverse relation, one of the screws 29 may be rotated independently of the other, thus effecting relative adjustment of the ends of the printing cylinder.

At the upper side of the carriage there are provided spaced upstanding portions 46 and 47 and a cover plate 48 bridging the said portions 46 and 47 and secured to their upper ends, forming a slideway upon the carriage in which is slidably mounted a bearing block 49 slightly wider than the carriage 95 and provided with overhanging guide flanges 50 and 51. A doctor knife shaft 52 is supported at its ends in the blocks 49 at the respective sides of the press, and is adapted to have reciprocatory movement in respect thereto. The blocks may be adjusted longitudinally of the slideway of the carriage by means of elongated screws 53 swivelled thereto at 54 and engaging threaded passages 53^a in the upstanding portion 47. 100

Upon the shaft 52 there is mounted in spaced relation, a plurality of blade clamps 55, the end clamps being preferably fixed by pins 55^a against rotation on the shaft, while the intermediate ones are loosely mounted between fixed collars 55^b. The clamps are provided in their forwardly projecting portions with slots 56 in which is secured the doctor blade 57 resting upon the printing cylinder, the blade being held in place by the pressure of a post 58 screwed into the upper side of the clamp, the said post being squared at its upper end as at 59 for engagement of a wrench. The post also serves as a support for a plurality of circular weights 60 mounted upon the clamp, the pressure produced by the weights being varied depending upon their number. A handle 61 is secured to one of the rigid clamps to facilitate swinging the doctor blade out of engagement with the printing cylinder. The intermediate clamps being loose, the blade will find its true engaging position at all points with the cylinder, any deficiency or curvature due to springiness 115 120 125 130

in the blade or bar being compensated by the weights causing the entire edge of the blade to rest squarely on the cylinder.

At one end of the shaft 52 there is mounted a depending yoke member 62 embracing an elongated cylindrical eccentric cam 63, the shaft 64 of which is journaled in bearing brackets 65 and 66 mounted upon the side of the frame 11, a gear 67 being provided upon one end of the shaft at the outer side of the bracket 66 which meshes with a similar gear 68 mounted upon a stud shaft 69 supported upon a bearing 66^a of the bracket 66, a beveled gear 70 being also provided upon the said shaft 69 which meshes with a beveled gear 71 provided upon one end of a shaft 72 journaled in the frame 11, a gear 73 being provided upon the other end of the said shaft which meshes with a substantially wider pinion gear 74 provided upon the shaft 18 of the printing cylinder, the greater width of the gear 74 permitting longitudinal shifting of the printing cylinder as will presently be more fully pointed out, without disengagement of the gears. Rotation of the printing cylinder will through the train of gears, impart rotation to the cam 63 and thereby cause to and fro reciprocating movement of the doctor blade, the effect of this being an even wiping and distribution of the ink upon the cylinder, free from streaks. The elongated cam 63 permits of adjustment of the bearing blocks 49 longitudinally of the carriage, without disturbing the cooperative relation between the cam 63 and the yoke member 62. Upon the supports or standards 10 and 11 there are rotatably secured by screws 170, locking cams 171 having operating handles 172 and which are adapted to be moved into engagement with the face of the upstanding head 24 to lock the carriage in its moved-in position, the screw 170 permitting of adjustment of the locking cam which, for this purpose, is spaced from the face of the side frame as at 173. By suitable adjustment of the cams 171, the bearing blocks may be clamped rigidly between the cams and the abutment screws 15. At the forward end of the carriage there is pivotally mounted upon a screw 174, a forked locking lever 175 provided with a handle 176 and adapted to be engaged about the shank of the screw 29 in the moved-in position of the carriage and disengaged when it is desired to move the carriage outwardly by operation of the said screw 29.

Below the printing cylinder there is provided an ink font 75 having an inking roller 76, the shaft 77 of which is journaled in the ends 78 and 79, the font being supported upon four arms 80 pivotally connected as at 81 to the four corners of the font and fixed upon supporting rock shafts 82 and 83, the shaft 83 being provided at its pro-

jecting end with a worm gear 84 engaging a worm 85 mounted in a bracket 86 secured to the frame 11, and provided at the end of its shaft with a hand wheel 87 adapted upon being turned, to rotate the shaft 83 70 and thereby cause the font to be raised or lowered into and out of inking relation with the printing cylinder, and also enabling the adjustment of the pressure relation between the inking roller and the printing cylinder. 75 The engagement of the worm and worm gear, it will be noted, acts as a lock to maintain the font in any desired position to which it is moved. When in its lowered position, the font is in such position in 80 front of the press that it may be supplied with ink with facility.

The main drive shaft 88 is disposed horizontally at one side of the press being journaled in a bearing 89 secured to the frame 10 85 and supported in the bearing 90 of a standard 91, rotation being imparted to the drive shaft through a gear 92 mounted thereon and a pinion 93 meshing therewith and driven by a motor or other suitable source 90 of power by the gear wheel 94. Upon the end of the shaft 88 there is provided a beveled pinion 96 meshing with the beveled teeth of a combination spur and beveled gear 97 mounted upon a stud shaft 98 journaled in the frame 10, the spur teeth meshing with and driving a gear 99 mounted upon one end of the shaft 18 of the printing cylinder. 95

Extending uprightly of the frame 10 and 100 journaled in bearing brackets 100, there is provided a shaft 101 provided at its lower end with a beveled pinion 102 meshing with the beveled gear teeth of the gear 97, and from which it receives its motion, the shaft 101 in turn imparting motion to superimposed printing units by means of beveled pinions 103 disposed relatively to the printing units and which engage the beveled teeth of the combined spur and beveled gears 110 similar to the gear 97, the superimposed units as previously pointed out, being similar to the units herein described; so that, exact synchronism of movement between the several printing units is obtained. The spur gear portion of the gear 97 is substantially 115 wider than the gear 99 so that longitudinal movement of the printing cylinder may be effected without disturbing the engaging relation of the gears. 120

In Figs. 4 and 5 I have shown in detail the construction of the gear 99, which is designed to enable the circumferential adjustment of the printing cylinder. Upon the reduced end 18^a of the shaft 18 there is mounted the hub 104 fixed against rotation relatively to the shaft by means of a key 105 and set screw 106 and provided with a flange 107 having an annular series of screw threaded holes 108 therein, a shoulder 109 provided 125

between the flange and the hub being provided with a plurality of radial passages 110 adapted to be engaged by a suitable rod to manually rotate the printing cylinder.

The toothed peripheral portion 111 of the gear is provided with an inwardly extending annular flange 112 and is recessed as at 113 at its rear side, the flange 107 of the hub engaging this recess. Diametrically opposite arcuate slots 114 and 115 are provided in the flange 112 in registering relation with the screw threaded holes 108 and adapted to receive retaining screws 116 and 117 engaged in two of the said holes 108, the projecting heads of the screws being provided with radial passages 118 therethrough adapted to be engaged by a rod to tighten the screws and thereby secure the flange 112 of the toothed periphery fixedly to the flange 107 of the hub. At each side of the slots 114 and 115 there are provided upon the flange 112 block portions 119 in which are adjustably mounted set screws 120 bearing upon the screw heads at each side and adapted by relative adjustment to effect minute adjustment of the screws in the slots 114 and 115. In order to adjust the printing cylinder circumferentially, the screws 116 and 117 are removed and the toothed peripheral portion of the gear being fixed by engagement with the gear 97, rotation of the printing cylinder is permitted relatively thereto. The cylinder is turned by means of a rod engaging the passages 110 to a position approximating the desired circumferential registering thereof, and the screws 110 and 117 are then engaged with the screw holes 108 substantially centrally of the slots 114 and 115, but are not tightened against the flange 112. By engagement of the set screws 120 with the sides of the screw heads and relative adjustment thereof, the desired accurate registration of the printing cylinder is obtained, and thereupon the screws 45 are tightened into place to securely fix the relation of the flanges 107 and 112.

In order to effect the longitudinal adjustment and registration of the printing cylinder, the projecting end of its shaft 18 opposed to the end supporting the gear 99, is provided with an annular groove 121 engaged by the yoke end 122 of an arm 123 provided intermediate its ends with a hub 124 having a screw threaded passage 125 therethrough engaged by a threaded adjusting shaft 126 journaled at one end in a bearing 127 fixed to the frame 11 and provided at its other end with a hand wheel 128 and which upon being rotated, causes the arm 60 to travel longitudinally of the shaft and thereby through its connection with the shaft 18, cause longitudinal movement and adjustment thereof. An apertured enlargement 129 is provided at the free end of the arm 123 engaging a guide rod 129^a fixed in

the frame 11 to prevent swiveling of the arm 123 and guide its movement.

The impression roller 130 has its shaft 131 journaled at its ends in sliding bearings 132 supported and guided upon guides 133 and 134 and respectively connected to adjusting screws 135 each extending through a nut 136 slidably in passages 137 at each end of the bracket 138 extending between and fixed to the side arms 10 and 11, the square heads 139 of the nut engaging the upstanding ends 140 of the bracket fixing it against rotation. Upon the respective ends of parallel shafts 141 and 142 extending between the upstanding ends of the bracket there are provided cams 143 and 144, the square head of the nut being held constantly in engagement with the said cams by means of springs 145 and 146 disposed in sockets 147 and 148 formed in the bracket above and below the passage 137, the said springs being adjustable as to tension by means of set screws 145^a and 146^a. Intermeshing pinions 149 and 150 are provided upon the respective shafts 141 and 142, and the lower shaft has 90 mounted thereon an arm 151 which upon being raised, will through the rotation of the shafts 141 and 142, turn the cams 143 and 144 so that the springs 145 and 146 force the nut 136 carrying the screw 135 outwardly 95 and thereby withdraw the bearings 132 and the impression roller carried thereby out of engagement with the printing cylinder.

The respective arms 151 of the superimposed printing units are connected by rods 152 so that movement of one of the arms will cause corresponding movements of the others and the throw-off of the several impression rollers will be simultaneous and equal. The lowermost arm 151 is connected by a rod 153 to an arm 154 provided upon the shaft 155 of a segment gear 156 which meshes with a pinion 157 provided upon the shaft 158 of a gear 159, a pinion 160 provided upon a shaft 161 mounted in a bracket 161^a meshing with the gear 159, a handle 162 being provided upon the shaft 161. By turning the handle 162, the train of gears 160, 159, 157 and 156 will swing the arm 154 upwardly, causing the arms 151 to be swung and the cams 143 and 144 to be turned to release the impression rollers.

The paper or web passes from between the printing cylinder and the impression roller over blankets 163 and thence from the lowermost blanket over a steam drying jacket 164.

The impression roller adjusting and releasing mechanism herein described is disclosed and claimed in my copending application Serial No. 315,603, filed August 6, 1919, and no claim is made herein to the particular mechanism except as to the adjustment and releasing relation between the printing cylinder and the impression roller.

With my improvements, accurate and positive adjustment and complete manipulation of the printing cylinder and its associated parts is obtained. In operation, the 5 press will be efficient and accurate and its precise adjustment will not be disturbed by the vibration and other force set up during operation of the press and furthermore adjustment is possible while the press is 10 running.

I have illustrated and described a preferred and satisfactory embodiment of my invention but it is obvious that changes may be made therein within the spirit and scope 15 thereof as defined in the appended claims:

I claim:

1. In a printing press, the combination of a printing cylinder, an impression roll, means for simultaneously and selectively adjusting the opposite ends of the printing cylinder relative to the impression roll, means for adjusting the pressure relation between the printing cylinder and the impression roll, means normally tending to 25 quickly separate the cylinder and roll, and quick acting releasing means operable counter to said last means for holding the cylinder and roll together in their adjusted pressure relation and adapted to be operated for 30 releasing said separating means.

2. In a printing press, the combination of a plurality of printing cylinders, an impression roll for each printing cylinder, means for simultaneously and selectively adjusting the opposite ends of each printing cylinder relative to its impression roll, means for independently adjusting the pressure relation between each printing cylinder and its impression roll, means normally 35 tending to separate the printing cylinders from their respective impression rolls, and releasing means operable counter to said separating means for holding the printing cylinders and impression rolls together in 40 their adjusted pressure relation and adapted to be actuated for releasing said separating means.

3. In a printing press, side frames provided with horizontal shelf portions, bearings 50 slideable upon said shelf portions, a printing cylinder supported in said bearings, an impression roll adapted to engage said printing cylinder, a carriage provided upon each of said shelf portions and respectively connected to said bearings to move the same therewith, a screw mounted in each of said shelf portions fixed against longitudinal movement, means on said carriages engaging said screws to effect movement of said carriages upon turning movement of said screws, and reversible ratchet means upon said screws adapted to turn said screws.

4. In a printing press, side frame provided 60 with horizontal shelf portions, bearings slideable upon said shelf portions, a printing

cylinder supported in said bearings, an impression roll adapted to engage said printing cylinder, a carriage provided upon each of said shelf portions and respectively connected to said bearings to move the same 70 therewith, a screw mounted in each of said frames fixed against longitudinal movement, means on said carriages engaging said screws to effect movement of said carriages upon turning movement of said screws, reversible ratchet means adapted to turn said screws, and upon reversal to effect turning movement in one or the other direction to respectively move said carriages in or out. 75

5. In a printing press, a printing cylinder, 80 an impression roll, carriage means for moving said printing cylinder into and out of engagement with said impression roll a shaft supported by said carriage means disposed parallel to the axis of said printing cylinder, and adapted to have reciprocating movement, a doctor knife supported thereby, an elongated cylindrical eccentric cam arranged parallel to the longitudinal movement of said carriage, and means on said shaft engaging said cam and adapted to maintain cooperative relation therewith in any position of movement of said carriage movement of said cam adapted to reciprocate said shaft of said doctor knife. 95

6. In a printing press, a printing cylinder, an impression roll, a shaft disposed parallel to said printing cylinder, an elongated doctor blade engaging said cylinder, a plurality of supporting means engaging said 100 blade and loosely mounted on said shaft in spaced relation, and weighting means mounted upon said respective supporting means and adapted to uniformly engage said blade with said cylinder throughout its 105 length.

7. In a printing press, a printing cylinder, an impression roll, a shaft disposed parallel to said cylinder, an elongated doctor blade engaging said cylinder, supporting means engaging said blade at its end portion and rigidly mounted on said shaft, and supporting means in spaced relation therebetween engaging said blade and loosely mounted on said shaft, and weighting means 110 mounted on said respective supporting means and adapted to uniformly engage said blade with said cylinder throughout its 115 length.

8. In a printing press, a plurality of printing cylinders, a plurality of impression rolls therefor, means for simultaneously and equally moving the ends of each of the printing cylinders to adjust the cylinders into and out of engagement with their respective impression rolls, means for simultaneously and equally moving all of the impression rolls toward and from their respective printing cylinders, and means for 120 adjusting the pressure relation between the 125 130

- printing cylinders and their respective rolls.
9. In a printing press, the combination of a plurality of printing cylinder and impression roll couples, individual means for each couple for independently adjusting the pressure relation between the cylinder and roll of each couple, independent means for simultaneously and selectively adjusting the ends of the printing cylinder of each printing couple into and out of engagement with their respective impression rolls, and means for simultaneously and equally moving all of the impression rolls toward and from their respective printing cylinders.
10. In a printing press having side frames, bearings slidable horizontally on the frames, a printing cylinder mounted in said bearings, an impression roll cooperating with the printing cylinder, a screw mounted in each of said frames and operatively connected to said bearings, an arm associated with each of the screws, like connections between the arms and the screws, each connection comprising a part movable to disconnect the arm from the screw, and a connection between said arms so that when each of the arms is connected to its respective screw, the screws may be simultaneously and equally adjusted by movement of one of said arms, whereas, upon movement of one of said parts to disconnect one of said arms from its respective screw, the other of said arms may be moved independently of the first mentioned arm so as to effect relative adjustment of the ends of the printing cylinder.
11. In a printing press having side frames, bearings slidable horizontally on the frames, a printing cylinder mounted in the bearings, an impression roll associated with the printing cylinder, means for adjusting said bearings to move the printing cylinder toward and from the impression roll, abutment means for limiting the inward movement of said bearings, and means movable into operative relation with the sides of the bearings opposite from the abutment and cooperating with the abutments to restrain the bearings rigidly against horizontal movement.
12. In a printing press having side frames, bearings slidable horizontally on the frames, a printing cylinder mounted in said bearings, an impression roll associated with the said cylinder, means for adjusting said bearings to move the printing cylinder toward and from the impression roll, adjustable abutment screws for limiting the inward movement of said bearings and cams movable into operative relation with the sides of the bearings opposite from the abutments, said cams being adjustable bodily toward and from said adjustment screws to enable the cams to cooperate with the screws to restrain the bearings rigidly against horizontal movement.
13. In a printing press having side frames, bearings slidable horizontally on the frames, a printing cylinder mounted in said bearings, an impression roll associated with the said cylinder, means for adjusting said bearings to move the printing cylinder toward and from the impression roll, adjustable abutment screws for limiting the inward movement of said bearings, cams movable into operative relation with the sides of the bearings opposite from the abutments, said cams being adjustable bodily toward and from said adjustment screws to enable the cams to cooperate with the screws to restrain the bearings rigidly against horizontal movement, and means for adjusting said bearings vertically while they are held against horizontal movement by said abutment screws and said cams.
14. In a press, a plurality of print and impression rollers, manually adjustable means for urging the impression rollers out of engagement with the print rollers, means acting against said manually adjustable means for advancing the impression rollers against said print rollers, and operating means connected to all of said advancing means to cause all of said advancing means to be operated simultaneously and equally.
15. In a press, a plurality of print and impression rollers, means for normally urging the impression rollers out of engagement with the print rollers, cam devices for advancing the impression rollers against said print rollers and against the action of said means, means for operatively connecting said cam devices, and manual operating means for said connecting means and including speed reducing elements, whereby all of said cam devices may be operated simultaneously and equally by hand.
16. In a press having print and impression rollers, means for withdrawing said impression roller from engagement with said print roller comprising an elongated screw swivelly connected at its inner end to said impression roller, a non-rotatable nut mounted on said screw, cam means engaging said nut, said nut being slidable toward said cam means and yieldably held in engagement therewith, and means to rotate said cam means to move said impression roller into and out of engagement with said print roller.
17. In a press having print and impression rollers, means for withdrawing said impression roller from engagement with said print roller comprising an elongated screw swivelly connected at its inner end to said impression roller, a non-rotatable nut mounted on said screw, a spring bearing against said nut to normally urge the impression roller away from the print roller, adjustment means engaging said nut adapted to move the same inwardly against the ten-

sion of the spring to engage said impression roller against said print roller, and means on said screw adapted to enable the same to be rotated in said nut to independently move said impression roller into and out of engagement with said print roller.

18. In a press, a plurality of print and impression rollers, means for normally urging the impression rollers out of engagement 10 with the print rollers, cam devices for advancing the impression rollers against said

print rollers and against the action of said means, means for operatively connecting together all of said cam devices, and independent manual operating means for simultaneously and equally operating all of said cam devices. 15

In testimony that I claim the foregoing as my invention, I have signed my name hereunder.

CHARLES F. DAUSMANN.
